UNITED STATES PATENT OFFICE.

LESTER J. BOWMAN, OF BAY CITY, OREGON.

SOCKET WRENCH.

Application filed March 13, 1924. Serial No. 698,969.

To all whom it may concern:

Be it known that I, LESTER J. BOWMAN, a citizen of the United States, residing at Bay City, in the county of Tillamook and State of Oregon, have invented a new and useful Socket Wrench, of which the following is a specification.

This invention relates to socket wrenches and more particularly to socket wrenches 10 of the power-driven type.

The primary object of the invention is to provide means for permitting the clutch mechanism of the device to slip when the nut under operation has been properly positioned, thereby insuring against the twisting 15 off of the bolt on which the nut is being positioned.

Another object of the invention is to provide a power wrench with a telescoping shank, whereby the tool may be adapted 20 for various usages.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 30 within the scope of what is claimed, without departing from the spirit of the invention.

Referring to the drawings:

Figure 1 is an elevational view of a car wrench constructed in accordance with the invention;

Fig. 2 is a sectional view taken on line 2-2 of Fig. 1, the body portion of the wrench being removed;

Fig. 3 is a sectional view through the shank of the wrench;

Fig. 4 is a longitudinal sectional view through the shank, one of the sections of the body of the wrench being removed;

Fig. 5 is a sectional detail view disclosing the controlling means and a portion of the shank; and

Fig. 6 is a sectional detail view disclosing the means for holding the sections of the shank in their extended positions.

Referring to the drawings in detail, the body portion of the wrench includes opposed sections 5 and 6, each of which sections being provided with apertured ears 7

to accommodate the securing bolts 8 whereby the sections of the body may be secured together.

A tubular extension 9 forms a part of the body portion and provides a bearing for the shank section 10 of the wrench, in which the shank section 11 moves, the shank section 11 having connection with the socket section 12, as clearly shown by Fig. 4 of the drawings. The section 10 is formed preferably with a square bore to accommodate the squared head 13 formed on one end of the shank section 11 so that rotation of the shank section 10 will result in a relative rotary movement of the sections 11 and 12 to accomplish the purpose of the invention.

Coiled spring 14 has one of its ends anchored to the partitioning wall 15 formed at one end of the section 10 of the shank, while the opposite end of the coiled spring is connected with the eye 16 of the shank section 11, so that when the shank section 11 is extended, the spring 14 will be placed under tension to return the section 11 to its inactive position, when the locking means which is in the form of a set-screw 17 is moved to its inactive position. As shown, this set-screw 17 contacts with the section 11 to hold the section 11 extended.

Disposed within the body portion 5 is an electric motor 18 which operates the pinion 19 that in turn transmits motion to the pinion 20 through the pinion 21 and shaft 22. Bearing 23 is disposed within the body portion 5 and supports the shaft 24 which is provided with a pinion 25 meshing with the pinion 20 to receive motion therefrom.

A friction clutch member is indicated at 26 and is secured to the outer end of the shaft 24, the clutch member 26 cooperating with the movable clutch member 27 to connect the shafts 24 and 28 and cause the operation of the socket supporting shank.

The shaft 28 is secured to the inner extremity of the socketed shank section 10 at 29, whereby rotary movement of the shaft 28 produces a relative movement of the shank to accomplish the purpose of the tool, the shaft 28 being shown as operating in the bearing 30. The pivoted arm 31 contacts with the clutch member 27 to move the clutch member into and out of operation, coiled spring 22' being provided and connected

with the arm 31 so that the coiled spring will tend to normally hold the clutch members disengaged.

The controlling mechanism forming an important feature of the invention embodies a sleeve 33 which collar is positioned over the tubular section 9 of the body portion in a manner to permit the same to slide longitudinally of the extension. Formed integral with the sleeve 33 is a threaded member 34 that is formed with a slotted portion to permit the sleeve to move over the stop 35, the stop being formed with a plurality of shoulders 36 arranged at various levels and rigidly attached to or formed integral with the extension 9.

As shown, the threaded member 34 accommodates the adjustable stop 36' which is designed to be rotated over the member 34 to partially close the slotted portion of the member 34 and contact with one of the shoulders when the sleeve has been moved to a predetermined position.

A hook member indicated at 37 is formed on the member 34 and receives one end of the coiled spring 38, the opposite end of the coiled spring being connected with the arm 31; and since the arm 31 is pivotally supported intermediate its ends as at 39, it will be obvious that as the sleeve 33 is moved along the extension 9, the arm will be operated to throw the clutch member 27 into engagement with the clutch member 26 to cause the operation of the device.

Thus it will be seen that if it is desired to position a half-inch nut on a bolt, it is obvious that the power required to position the nut would be relatively slight, therefore the sleeve 33 would be moved along the collar 9 until the screw-threaded stop 36' contacted with the first shoulder of the stop 35. As the wrench is operating, it is obvious that when the nut is properly positioned or driven home, the continued rotation of the shank 10 would overcome the tension of the

coiled spring 38 to the end that the clutch members would slip and prevent the further rotation of the nut under operation.

If it is desired to position a one-inch nut, it is obvious that by rotating the member 36' on the member 34, to cause the lower end of the member 36 to clear the first notch of the stop 35 when the sleeve is moved along the tubular section 9 the spring 38 will be placed under greater tension to cause the clutch members to be held into engagement a greater length of time.

What is claimed as new is:—

1. In a device of the character described, a body portion, a tubular shank supported by the body portion, a wrench shank slidably mounted within the tubular shank and carrying a wrench socket at its outer end, a coiled spring positioned in the tubular shank, one end of the coiled spring being secured within the tubular member, the opposite end of the spring being secured to the slideable shank to normally draw the slideable socket carrying shank inwardly, and means for holding the slideable shank in various positions of adjustment.

2. In a device of the character described, a body portion, a tubular shank supported by the body portion, a stop mounted on the body portion and having a plurality of shoulders, a sleeve operating over the tubular shank, a threaded member forming a part of the sleeve and having a slotted portion to permit the threaded member to be moved over the stop, and an adjustable member on the threaded member and adapted to be adjusted longitudinally thereof, said adjustable member adapted to move into engagement with the shoulders to restrict movement of the sleeve, and a clutch device controlled by the movement of the sleeve.

In testimony that I claim the foregoing as my own, I have hereto affixed my signature.

L. J. BOWMAN.
